HINGE

James T. Atwood and Lewis C. Smith,
Rockford, Ill.

Application April 4, 1938, Serial No. 199,806

8 Claims. (Cl. 16—128)

This invention relates to hinges for use on the doors of motor vehicles and has for its principal object the provision of a hinge of sheet metal construction which, by reason of novel formation of the parts, is not only stronger and of better appearance but can be made from strip steel of lighter gauge than has heretofore been found necessary, so that a real saving in cost is effected.

One of the principal features of the hinge of our invention is the box or channel formation of the outer ends of both the outer and inner hinge members, these portions being in reverse relation interfitting and having a pintle entered through aligned openings in the abutting upper and lower flanges thereof. This not only results in a hinge of pleasing appearance when viewed from either side, but the two U or channel sections make for greatly increased strength and rigidity.

In accordance with the novel method of manufacture both hinge members are made from strip steel of the same width and the box or channel end portions are formed so that the top and bottom flanges of these portions are made from the marginal edge portions of the strip bent inwardly in planes at right angles to the strip, the end portions which project from the body being, therefore, a fraction of the width of the attaching portions that are fastened to the door and body. In that way, there is the desired width for secure attachment to the door and body, and at the same time the projecting pivotally connected portions which are of reduced width but channel section are of ample strength to take care of the load of the door in connection with which the hinge is used. The connecting webs between the wide attaching shank and the top and bottom flanges of the narrow channel-shaped ends account for much of the strength and rigidity in this hinge. The fact that a hinge made in accordance with our invention will have such wide attaching portions and such strength built into the pintle receiving portions, by reason of the narrow channel section thereof and the webs reinforcing the same, permits use of lighter gauge strip steel throughout, with a resulting saving in cost.

Still another object is to provide hinges of the kind described in which, in the case of the fully exposed hinges, the connecting webs between the wide attaching shank portions and the top and bottom flanges of the channel-shaped end portions extend at different angles to the vertical line through the pintles of the two hinges on a door, according to the distance which the hinges project from the body, whereby to make for good

appearance of the exposed hinge portions while still retaining the desired structural strength and rigidity. However, it is also an important object of our invention to have the hinges set back into the body so as to leave only the narrow channel-shaped end portions projecting, with a view to making the hinges as inconspicuous as possible, while at the same time retaining the wide attaching shanks and the other features referred to which give the desired strength and rigidity.

The invention is illustrated in the accompanying drawings, in which—

Figure 1 is a horizontal section through the edge portion of a door and the cooperating pillar on the body showing in plan view a hinge made in accordance with our invention;

Figs. 2 and 3 are, respectively, a front view and side view of the hinge of Fig. 1 removed from the car;

Fig. 4 is a longitudinal section through the hinge on the line 4—4 of Fig. 2;

Fig. 5 is a sectional detail on the line 5—5 of Fig. 1;

Figs. 6 and 6a are sections similar to Fig. 5 showing modified or alternative constructions of the pintle bearing;

Fig. 7 is a view of an automobile door pillar illustrating a pair of hinges thereon and indicating the different formation of the projecting portions of the upper and lower hinges;

Fig. 8 is a view similar to Fig. 1 showing a similar hinge set back into the body, leaving only the narrow end portion of the hinge exposed as appears in Fig. 9, which is a view looking at the outside of the door and body, showing a front view of as much of the hinge as is left exposed;

Fig. 10 is a longitudinal vertical section through the hinge taken on the line 10—10 of Fig. 8, and

Fig. 11 is a cross-section on the line 11—11 of Fig. 8.

Similar reference numerals are applied to corresponding parts throughout the views.

Referring first to Figs. 1—7, the numeral 12 designates the door of a motor vehicle and 13 designates the pillar on the body, but it will soon be evident that although the outer hinge member 14 is here shown as attached to the edge portion of the door 12 by bolts 15 it may be attached to the pillar instead, and the inner hinge member 16 shown attached to the pillar 13 by bolts 17 may be attached to the door. The outer hinge member 14 is formed from strip steel of uniform width and comprises an attaching shank portion 18 and an outer end portion 19 integral with the shank 18 formed to provide a channel or box-shaped

section 20, the upper and lower flanges or walls 21 and 22 of which are parallel and in a plane at right angles to the plane of the attaching shank 18 and connected therewith by webs or flanges 23 and 24 which extend downwardly and upwardly from the top and bottom of the shank at obtuse angles to the flanges 21 and 22, respectively. In like manner, the inner hinge member 16 has an attaching shank portion 25 formed from a piece of strip steel of the same width as the shank 18, and the outer end portion 26 thereof is formed to a channel or box section 27 providing upper and lower flanges or walls 28 and 29 in planes at right angles to the plane of the shank 25 and joined to the shank by integral angularly extending upper and lower webs or flanges 30 and 31, respectively. The flanges 28 and 29 fit neatly between the flanges 21 and 22 as clearly appears in Fig. 5, and a pintle 32 entered through registering holes 33 and 34 in the flanges of the two respective hinge members serves to pivotally connect the same. The pintle 32 has a short serrated or knurled portion 35 immediately below the head of the pintle which will have a drive fit in the upper hole 33 in the outer hinge member 14 so that the pintle turns with the outer hinge member as a unit in the opening and closing of the door and works in the holes 34 in the other hinge member 16.

30 The hinge members 14 and 16 can be produced from the same width of strip steel at unusually low cost, because the material cost is low to begin with and simple punch press operations suffice to bend, form, and draw the marginal edge portions of the strip to form the top and bottom flanges of the channel-shaped end portions 20 and 27 and the connecting webs 23-24 and 30-31. The channel-shaped end portions 20 and 27 have great strength and rigidity, due to the short span between the pintle receiving flanges 21-22 and 28-29. The intermediate tapered connecting portions between the pintle bearing portions and the shank portions also have great structural strength and rigidity, because the webs 23-24 and 30-31 give these portions channel section. The webs mentioned buttress the outer pintle bearing ends of the hinge members from above and below, carrying the reinforcement out close to the pintle, as shown, so that the weight 50 of the door will not cause the hinge to sag. In fact the construction is of such strength, due to the bracing referred to, that we have found that much lighter gauge steel can be used, $\frac{1}{8}$ " thickness being considered entirely feasible and practical as against $\frac{1}{4}$ " or even $\frac{5}{8}$ " thickness used heretofore. Furthermore, the fact that the channel-shaped end portions of the hinge members have their top and bottom flanges and their connecting webs formed from the marginal edge portions of the strip, it follows that the full width of the strip is left for the attaching shank portions 18 and 25, thereby meeting the requirement so far as wide attaching ends are concerned. Naturally, with this full width in the attaching shanks, the fastening bolts can be placed as far apart as desired so that the hinges can be fastened securely to the door and body and there is no danger of the hinges working loose. Still greater strength and rigidity can be 60 built into the hinge by forming channel-shaped ribs 36 and 37 longitudinally of the shanks 18 and 25, respectively, extending outwardly through the intermediate portions where the connecting webs 23-24 and 30-31 are, to the channel-shaped end portions 20 and 27, as clearly appears

in Figs. 1, 2 and 3. The hinge seats on the door and pillar will be recessed to accommodate these ribs, as indicated at 38-39 in Fig. 1. Of course, this is only one of a variety of ways in which the hinge members may be ribbed to add strength and stiffness. For example, in Figs. 8 to 11, the hinge members 14' and 16' are shown provided with inwardly projecting ribs 36' and 31' to afford added strength and stiffness without interfering with attachment to flat hinge seats on the door 12' and body 13'. Then, too, the longitudinal edges of the shanks 18' and 25' are bent at right angles to provide reinforcing flanges 40 and 41 which constitute a continuation of the ends of the webs 23', 24', 30' and 31', as best 15 appears in Figs. 8 and 10.

Where the hinges project to a substantial extent from the body, and the lower hinge projects to a different extent than the upper hinge, as shown in Fig. 7, we prefer to have the webs 23-24 and 30-31 on the upper hinge A at a smaller acute angle with respect to the vertical line through the pintles of the two hinges A and B than the corresponding connecting webs on the lower hinge B, because it greatly improves the appearance and at the same time extends the reinforcement through the intermediate portions of the hinges between the channel-shaped pintle receiving portions and the attaching portions so that the hinges will have the requisite strength 30 to support the door. In some cars where the body does not have such an extreme outward bulge in its curved outer surface and one may therefore locate the hinging axis closer to the body, we propose to set the hinges back into the 35 body as shown in Figs. 8 and 9, leaving only the narrow channel-shaped pintle receiving portions 20-27 of the hinges projecting. In some cases where the extent of outward bulge of the outside of the body will not permit setting the hinges 40 back into the body to quite this extent, substantially the same effect can be obtained so far as appearance is concerned, even though the hinging axis is spaced farther out from the body if the sheet metal on the outside of the door indicated 45 at 42 in Fig. 8 is simply deflected or bulged outwardly over the intermediate webbed portions of the hinges. In that way, the only portions of the hinges left exposed are the narrow channel-shaped pintle receiving portions which present a 50 neat and attractive appearance and are fairly inconspicuous.

Another advantage in the present construction is the elimination of noise incident to the rush of air past the projecting hinges; the reduced 55 width of the projecting portions and the fact that they are furthermore of inclosed construction, without pockets or recesses to scoop the air, makes these hinges substantially silent. Then, too, there is the advantage with this completely enclosed hinge of protection against dust and dirt getting into the pintle bearings, and the fact that water, snow, and sleet are excluded more effectively than with other constructions with which we are familiar.

The pintle bearings 34, disclosed in Fig. 5, are somewhat larger in diameter than has been the accepted practice with hinges of the prior conventional unimproved type, the thought being that with pintles of enlarged diameter there will be 70 sufficient bearing contact to make additional bearing means unnecessary. However, in cases where the weight of the door is such that additional bearing surface for the pintles seems necessary, we may provide a tubular bearing 75

member 43 preferably curled from a single piece of sheet metal for economy in production and set in holes 44 in the flanges 28a and 29a of the channel-shaped outer end 27a of the inner hinge member. The pintle 32 in such a construction will turn with the outer hinge member and have a working fit in the bore 45 of the tubular bearing 43 in the inner hinge member. The tubular bearing may be secured in place in the inner hinge member in any one of a variety of ways; it may be pressed in place in the holes 44 or entered freely in these holes and secured by slightly swedging the ends or by prick punching around the ends of the bearing member at the holes 44 in the flanges 28a and 29a.

Another alternative construction is illustrated in Fig. 6a in which the bearing holes 34 in the flanges 28b and 29b are elongated by forming the metal, as indicated at 46, after piercing. In this construction, as in the ones shown in Figs. 5 and 6, the pintle 32 turns with the outer hinge member and has a working fit in the inner hinge member.

It is believed the foregoing description conveys a good understanding of the objects and advantages of our invention. The appended claims have been drawn with a view to covering all legitimate modifications and adaptations.

We claim:

1. A hinge comprising a pair of one-piece sheet metal inner and outer hinge members, each comprising a body providing an attaching shank portion with an extension at one end having opposed marginal edge portions extending laterally defining top and bottom flanges and the middle end portion therebetween longitudinally curved providing therewith a channel box portion of less width than the shank portion, said shank and channel portions being connected by strengthening and stiffening webs in converging transverse planes extending from the top and bottom of the outer end of the shank portion and forming continuations of the top and bottom flanges of the channel box portion, the channel box portions of the two hinge members opening toward one another and the channel box portion of the inner hinge member fitting within the channel box portion of the outer hinge member, the top and bottom flanges of the inner hinge member rotatably abutting the inner faces of the related flanges of the outer hinge member, and means pivotally connecting the outer ends of said hinge members.

2. As an article of manufacture, a hinge member comprising a sheet metal body providing an attaching shank portion with an extension at one end having opposed marginal edge portions extending laterally defining parallel top and bottom pintle bearing flanges and the middle end portion therebetween longitudinally curved providing therewith a channel box portion of less width than the shank portion, said shank and channel portions being connected by strengthening and stiffening webs in converging transverse planes extending from the top and bottom of the outer end of the shank portion and forming continuations of the top and bottom flanges of the channel box portion.

3. A hinge as set forth in claim 2, including, an inwardly extending flange on at least one of the longitudinal edge portions of the shank, constituting an extension of the inner end of the adjacent connecting web.

4. A hinge member comprising a body providing an attaching shank portion and a pintle bear-

ing portion integral with the outer end thereof, the pintle bearing portion having substantially parallel opposed walls in transverse relation to the plane of the shank portion, at least one of said opposed walls being connected to the adjacent longitudinal edge portion of the shank by an integral flange extending inwardly from the inner end of said wall at an acute angle to the axis of the pintle bearing portion to the longitudinal edge of said shank, the flange tapering in width from its junction with the aforesaid wall toward its junction with the longitudinal edge portion.

5. A hinge member comprising a body providing an attaching shank portion and a pintle bearing portion integral with the outer end thereof, the pintle bearing portion having substantially parallel opposed walls in transverse relation to the plane of the shank portion, and said opposed walls being connected to the adjacent longitudinal edge portions of said shank by integral flanges extending inwardly from the inner ends of said opposed walls in diverging relation to one another and at acute angles to the axis of the pintle bearing portion to the longitudinal edges of said shank, the flanges tapering in width from their junctions with said opposed walls toward their junctions with the longitudinal edge portions.

6. A hinge comprising inner and outer members adapted to be pivotally connected by a pintle, each of said members comprising an attaching shank portion and a hood portion formed integral with the outer end thereof, the hood portion having substantially parallel opposed walls in transverse relation to the plane of the shank, the hoods of said inner and outer members being reversely arranged and inter-fitting, a pintle entered through registered openings provided in the opposed walls of said hoods, the opposed walls of each hood being connected to the adjacent longitudinal edge portions of the associated shank by integral flanges extending inwardly from the inner ends of said walls in diverging relation to one another and at acute angles to the pintle axis to the longitudinal edges of said shank, the flanges tapering in width from their junctions with the walls toward their junctions with the longitudinal edge portions, and the flanges on the inner member fitting within the angle defined by the flanges of the outer member in the closed position of said members.

7. In a pintle hinge, a hinge member comprising a body portion providing an attaching shank portion and a narrower perforated pintle receiving portion of channel-shaped cross section, the channel-shaped pintle receiving portion being connected to the shank portion by an intermediate portion of channel cross section decreasing in depth but increasing in width from the pintle receiving portion to the shank portion.

8. A hinge comprising two members, each comprising a body providing an attaching shank portion and a narrower perforated pintle receiving portion of channel-shaped cross section, the channel-shaped pintle receiving portions of the two members opening toward one another and inter-fitting for relative pivotal movement with respect to one another, a pintle pivotally connecting the members by their pintle receiving portions, the channel-shaped pintle receiving portions of both members being connected to the shank portions by intermediate portions of channel cross section decreasing in depth but increasing in width toward the shank portions.
